ELECTRIC BLASTING INITIATOR

Charles R. Johnson, West Chester, Pa., and Roland R. Nydegger, Wilmington, Del., assignors to E. I. du Pont de Nemours & Company, Wilmington, Del., a corporation of Delaware

Application December 24, 1937, Serial No. 181,644

7 Claims. (Cl. 102—10)

The present invention relates to electric blasting initiators and more particularly to a novel and improved method for the manufacture of water impervious electric blasting initiators.

5 As is well known, the usual procedure for the manufacture of electric blasting initiators comprises embedding the leg wires in a hard cast plug of sulfur-containing material and subsequently sealing this unit into place in a loaded 10 shell by means of thermoplastic water-proofing compositions or similar sealing means. Such a procedure is not adaptable to a mechanical method of assembly, but includes several complicated and undesirable hand operations, involving both molten materials and loaded shells. 15 Furthermore, due to the thermoplastic nature of the sealing compositions required, the resulting assembly fails to provide adequate moisture protection for the explosive charge under varying 20 conditions of storage, and changing temperatures.

The object of the present invention is a new and improved electric blasting initiator. An additional object is an electric blasting initiator 25 which is readily adaptable to mechanical assembly. Additional objects will be apparent from the following detailed description of our invention.

We have found that these objects are accomplished and the foregoing disadvantages overcome by manufacturing electric blasting initiators according to the process of our invention, which comprises molding and compressing a 30 heated material about the leg wires of the electric blasting initiator to form a resilient plug, that is, a rubber-like plug, and to form an extension of the same material as said plug and of decreased area of cross-section beyond the base of 35 said plug and integral therewith, said reduced extension surrounding and closely adhering to said leg wires, providing a waterproof seal between said wires and plug. The material employed may be a rubber composition or any other vulcanizable or thermoplastic material possessing 40 resilient properties, that is, any rubber-like material. By the term "rubber-like" we refer to those properties generally possessed by rubber compositions, namely, elasticity, springiness, extensibility, and in one sense of the word, compressibility. As brought out later on in our specification, this capacity of the plug material for rebounding, springing back and returning to its 45 original shape without permanent deformation, which is characteristic of rubber and similar compounds, is effective in the plug of our in-

vention for the purpose of forming a water-proof closure by crimping the shell on the blasting initiator into the rubber-like plug.

The reduced extension beyond the base of the plug and integral therewith may take any shape 5 provided that it has a decreased area of cross-section with respect to that of the body of the plug of which it is an integral part, and surrounds and closely adheres to the leg wires. For example the extension may be cylindrical in shape, 10 or it may take the form of a pyramid, truncated cone, wedge, or the like. It may be in one piece or in two separate portions, one surrounding each leg wire. Preferably, however, we employ an extension so constructed that the ratio of the 15 area of cross-section of said extension to the combined area of cross-section of the leg wires is relatively small. We prefer to employ an extension from $\frac{1}{16}$ to $\frac{1}{8}$ of an inch in thickness, and find one of $\frac{3}{16}$ of an inch in thickness to be 20 ideal. We have obtained desirable results with an extension in a single piece, preferably extending lengthwise across the base of the plug, so that this lengthwise dimension of the extension across the base of the plug will approximate to the 25 diameter of the plug itself, the thickness of the extension across the base of the plug being appreciably less than the diameter of the plug itself and preferably being within the range noted in the foregoing. This extension arrangement is 30 desirable in order to effect an absolutely water-proof relationship between said leg wires and said plug, especially in mass production. Likewise the extension is of particular advantage for rendering the completed initiator assembly resistant 35 against any forces which would otherwise tend to pull the leg wires and plug from the shell.

In order to describe our invention more clearly, we shall refer to the attached drawing which 40 illustrates a preferred embodiment thereof. This is done solely by way of illustration and is not to be regarded as a limitation upon the scope of our invention, since many variations within the purview of this invention will be readily apparent to any one skilled in the art.

Referring generally to the various figures of the drawing, Fig. 1 is a vertical section of the preferred form of resilient plug according to our invention. Fig. 2 is an end view of said plug showing the extension thereon. Fig. 3 is a vertical section of a complete electric blasting cap assembly containing the resilient, rubber-like plug of our invention. Figures 4, 5 and 6 are 45 similar views of slightly different embodiments of 50 55

the extension portion of the plug of our invention.

Similar characters are used throughout the several views and in the following description to 5 designate corresponding parts.

Referring in greater detail to the drawing of the finished plug, the bare ends 14 of the leg wires are shown in Fig. 1 to be embedded in the body of the rubber plug 17, and also in the relatively narrow extension 15, which extends beyond the central portion of the base of said plug and is integral therewith. It will be noted that the insulated portions 19 of the leg wires, are likewise embedded in the plug 17. The labyrinth 18 10 which is not essential to the finished product of our invention has been formed immediately above the bridge plug as a result of the preferred process for molding said plug about the leg wires, as described in detail in our copending application referred to in the following. The bridge wire 16 connects the bare ends of the leg wires.

In Fig. 2 the general relative proportions of the area of the cross-section of the extension 15 and that of the bridge plug 17, may be observed. The leg wires 14 are shown in position and are connected by the bridge wire 16.

In Fig. 3 may be seen the location of the resilient, that is, rubber-like bridge plug in the assembled electric blasting cap. The plug is crimped in place in the open end of the electric blasting cap shell 23, said closure being effected by means of the internal annular beads or grooves 24 in the shell wall, whereby the plug is gripped and held firmly in position. The bridge wire 16 is embedded in an ignition composition 20, below which is a priming composition 21 and a base charge 22.

In Figures 4, 5 and 6, the extension 15 is depicted in the form of a pyramid, a truncated cone, and separated extensions around each leg wire, respectively.

A detailed description of the preferred molding process of our invention is described in copending application Serial No. 244,334, filed Dec. 7, 1938.

After the desired molding period, the two sections of the mold are separated and the wires, enclosed in the rubber plug of preferred characteristics, are removed. Whereas any vulcanizable resilient material, that is, any material having springy, rubber-like properties including the so-called rubber substitutes, as well as varying degrees of vulcanized rubber may be employed for the formation of our improved plug, we prefer to use a crude rubber composition.

The finished bridge plug is then introduced into the open end of the charged electric blasting cap shell 23 and crimped into a water impervious relationship with said shell.

Our electric blasting initiator offers outstanding advantages over the art. By the development of an initiator wherein no waterproofing or sealing materials are necessary, we have eliminated the hazards inherent in the old process of pouring molten materials by hand into a loaded shell. In our invention, the bridge plug is simply crimped in place in the loaded shell, a step which may be readily mechanized, and carried out at normal temperatures. Furthermore, our assembly is an exceptionally strong one mechanically, thus permitting greater exposure security without damage to the blasting cap. Tests have demonstrated that blasting caps made by our invention are capable of consistently withstanding much higher water pressures than the ordinary type wherein waterproofing and sealing materials are em-

ployed. In addition, the elimination of such waterproofing and sealing compounds makes possible an initiator of much smaller length.

In the foregoing, we have described our improved initiator in detail. It will be apparent, however, that many variations may be made without departing from the scope of our invention. We intend, therefore, to be limited only by the following claims.

We claim:

1. A water impervious electric blasting initiator adapted to mechanical assembly, which initiator comprises a bridge plug of rubber-like material formed about the leg wires of said initiator, said plug having at its base an extension of the same material having a decreased area of cross-section with respect to that of the body of said plug and integral therewith, the material of said extension surrounding and closely adhering to said leg wires forming a waterproof seal between said leg wires and plug, and a charged shell crimped about said plug in waterproof relationship therewith. 10

2. A water impervious electric blasting initiator adapted to mechanical assembly, which initiator comprises a bridge plug of rubber-like material formed about the leg wires of said initiator, said plug having at its base an extension of the same material and integral with same plug such that the ratio of the area of cross-section of said extension to the combined area of cross section of the leg wires is small, the material of said extension surrounding and closely adhering to said leg wires forming a waterproof seal between said leg wires and plug, and a charged shell crimped about said plug in waterproof relationship therewith. 20

3. A water impervious electric blasting initiator adapted to mechanical assembly, which initiator comprises a bridge plug of rubber-like material formed about the leg wires of said initiator, said plug having a reduced extension of the same material integral with its base, the material of said extension surrounding and closely adhering to said leg wires forming a waterproof seal between said leg wires and plug, and a charged shell crimped about said plug in waterproof relationship therewith. 30

4. A water impervious electric blasting initiator adapted to mechanical assembly, which initiator comprises a bridge plug of rubber-like material formed about the leg wires of said initiator, said plug having at its base and integral therewith an extension such that the ratio of the area of cross-section of said extension to the combined area of cross-section of the leg wires is relatively small, the material of said extension surrounding and closely adhering to said leg wires forming a waterproof seal between said leg wires and plug, and a charged shell crimped about said plug in waterproof relationship therewith. 40

5. A water impervious electric blasting initiator adapted to mechanical assembly, which comprises a bridge plug of rubber-like material vulcanized about the leg wires of said initiator, said plug having a reduced extension beyond its base and integral therewith, the material of said extension surrounding and closely adhering to said leg wires forming a waterproof seal between said leg wires and plug, and a charged shell crimped about said plug in waterproof relationship therewith. 50

6. A water impervious electric blasting initiator adapted to mechanical assembly, which comprises a bridge plug of rubber-like material vulcanized about the leg wires of said initiator, said plug 60

having an extended portion of the same material at its base and integral therewith characterized by a cross-section, which does not greatly exceed the cross-section of the leg wires, the material of said extended portion surrounding and closely adhering to said leg wires to form a water-tight seal between the leg wires and the plug.

7. A water impervious electric blasting initiator adaptable to mechanical assembly, which comprises a bridge plug of rubber-like material

vulcanized about the leg wires of said initiator, said plug having an extension of the same material at its base and integral therewith characterized by a cross-section, one dimension of which does not greatly exceed the diameter of the leg wires, the material of said extension surrounding and closely adhering to said leg wires to form a water-tight seal between the leg wires and the plug.
